UNITED STATES PATENT OFFICE.

PATRICK S. O'DONNELL, OF CHICAGO, ILLINOIS, ASSIGNEE, BY MESNE ASSIGNMENTS,
TO AUTOMATIC MAGAZINE CIGARETTE BOX CO., OF CHICAGO, ILLINOIS, A COR-
PORATION OF ILLINOIS.

CIGARETTE-CASE.

1,131,856.

Specification of Letters Patent. Patented Mar. 16, 1915.

Application filed March 12, 1914. Serial No. 224,258.

To all whom it may concern:

Be it known that I, PATRICK S. O'DONNELL, a subject of the King of Great Britain, residing at Chicago, in the county of 5 Cook and State of Illinois, have invented certain new and useful Improvements in Cigarette-Cases, of which the following is a specification.

This invention relates to cases or holders 10 for containing cigarettes or cigars and has for its main object to provide a simple, convenient, and easily manipulated case or holder that will completely protect the articles from injury, that can be conveniently 15 carried in the pocket of the user, and that will facilitate the withdrawal of the articles successively as used.

To this end the invention comprises essentially a box, containing a spring-actuated follower acting laterally upon a row 20 of cigarettes therein, and an ejector for withdrawing the foremost cigarette by an endwise movement, all constructed and organized substantially as hereinafter described and defined in the appended 25 claims.

The article of my invention, its mode of use, and the advantages inhering therein will be readily understood when considered 30 in connection with the accompanying drawing which illustrates one practical embodiment of the invention, and in which—

Figure 1 is a top plan view of the cigarette case with the cover thrown open and 35 showing a row of cigarettes therein, and with the spring-pressed follower in fully retracted and locked position. Fig. 2 is an edge view of the same as seen from the left of Fig. 1. Fig. 3 is a cross-sectional view 40 on the line 3—3 of Fig. 1. Fig. 4 is a top plan view of the case in close position with the cover locked, and a portion of the cover and front wall broken out to disclose underlying parts. Fig. 5 is a horizontal section 45 showing the relative positions of the parts when the box has been about half emptied, and also showing in dotted lines the withdrawn position of the ejector and the foremost cigarette partially withdrawn thereby. Fig. 6 is an inner face view of the 50 follower-head. Fig. 7 is a perspective detail illustrating a catch for holding the follower in fully retracted position.

Referring to the drawing, 10 designates

as an entirety the body of the box, which, 55 in the form shown, is a rectangular structure of slightly greater thickness than the cigarettes adapted to be contained therein and has rounded front and rear ends 11 and 12, respectively, flat side edges 13, and 60 a flat hinged cover 14 adapted to close the open upper side of the box.

Slightly inwardly of what I term the foremost end wall 11 is secured an inner or false end wall 15, concave in cross-section, which 65 wall, as shown in Fig. 5, extends something more than half the width of the box, and forms an abutment or stop for the foremost cigarette. In one side edge 13 and just inwardly of the outer end of the inner wall 70 15 is formed an exit opening 16 that is of slightly greater diameter than the diameter of a cigarette such as the case is designed to contain. Slidably mounted against the rear or outer side of the wall 15 is an ejector 75 17 that is formed in its inner end with an inwardly extending foot 18 normally lying within a countersink or recess 19 in the other side edge of the box, and on its outer end has a laterally extending lug or handle 80 20 normally overlying the side edge wall below the opening 16 and adapted to be engaged by the thumb or finger of the user to withdraw the ejector. This ejector is spring-retracted, for which purpose it is 85 provided on its rear side with a lug 21 to which is attached one end of a tensile spring 22, the other end of which spring is attached to a similar lug 23 on the back side 90 of the inner end of the fixed wall 15, said lug 23 extending through a longitudinal slot 24 in the ejector 17.

The follower which acts to normally force the row of cigarettes against the wall 15 in position to be extracted by the ejector 95 comprises, in the form shown, a follower-head designated as an entirety by 25, a shank or stem 26, herein shown as of lazy tongs form, and tensile springs 27 which connect the foremost arms of the lazy tongs 100 thereby constantly tending to expand the latter and advance the follower-head. Extending through the forward ends of the foremost arms of the lazy tongs are cross-pins 28 to which the ends of the springs 27 105 are connected, and which cross-pins also slidably engage slots 29 (Fig. 5) in the opposite side walls of the follower-head 25.

The rear ends of the foremost arms of the lazy tongs are preferably pivotally connected to the ends of a cross-bar 30.

The cover 14 is locked in closed position 5 by means of a small knob 31 on the inner side of the cover near its free edge which passes through a hole 32 in the upper side wall of the case and is engaged by the forked end 33 of a slide 34 that is secured 10 by a pin-and-slot mount 35 to the under side of the upper wall of the case, and at its outer end has a laterally extending lug or handle 36 adapted to be engaged by the thumb or finger of the user to withdraw the 15 slide and unlock the cover.

In its fully retracted position, the follower is contained mainly within the rounded end portion 12 of the case, as shown in Fig. 3, and is locked in such position when 20 the slide 34 is in the retracted position shown in Fig. 1 by means of a catch 37 formed on the upper side wall of the follower-head 25 which, as the follower-head is pushed back, snaps beneath and behind 25 a laterally bent tooth 38 formed on the forked inner end of the slide 34, to facilitate which the lower edge of the tooth 38 is given a rounded or cam form 38' as best shown in the detail view Fig. 7, the catch 30 37 having sufficient elasticity to flex beneath the cam edge 38' of the tooth and snap up behind its rear edge. The follower is thus locked in retracted position during the loading of the box; and when this is accomplished, the cover is closed, and the slide 34 pushed in which simultaneously locks the cover and, by carrying the tooth 38 beyond the catch 37, the follower is at once released and exerts its pressure upon the foremost 35 cigarette of the row. When the user wishes to extract a cigarette he merely seizes the lug 20, withdraws the ejector 17, the foot 18 of which by acting endwise upon the foremost cigarette forces the latter sufficiently 40 through the exit hole 16 to enable it to be readily grasped and withdrawn, the ejector returning to normal position when released under the action of spring 22.

From the foregoing it will be readily apparent 50 how the article described effects the stated purposes and objects of the invention. My improved cigarette case, which, as hereinabove suggested, might, of course, be used for cigars or other articles of the general 55 form of cigarettes and cigars, completely incases or incloses the articles, thus protecting them from breakage or other injury, and forms a simple and compact object readily carried in the pocket of the user.

Without limiting myself to the precise details of structure and arrangement shown and described, I claim—

1. In a cigarette case, the combination of a box having a delivery opening in one side 65 edge and a hinged cover forming in part

one side wall thereof, a spring-actuated follower in said box operating to exert side-wise pressure on a row of cigarettes in said box and maintain the foremost cigarette opposite said opening, an ejector operative 70 to force said foremost cigarette through said opening, and a lock-bar serving at one limit of its movement to unlock said cover and lock said follower in retracted position and at the other limit of its movement to lock 75 said cover and release said follower.

2. In a cigarette case, the combination of a box adapted to hold a row of cigarettes arranged side-by-side and having a delivery opening in one side edge, a spring-actuated 80 follower in said box operating to press the cigarettes laterally and maintain the foremost cigarette of the row opposite said opening, a stop-plate extending partially across said box just beyond said opening 85 and formed with a rearwardly extending lug, an ejector slidably mounted transversely of the box directly behind said stop-plate and slotted lengthwise to accommodate said lug of the stop-plate, an inwardly 90 projecting foot on said ejector extending transversely of and limited as to its outward movement by the inner end of said stop-plate, a lug on the back of said ejector, and a tensile spring connecting said lugs. 95

3. In a cigarette case, the combination of a box adapted to hold a row of cigarettes arranged side-by-side and having a delivery opening in one side edge and a hinged cover, a spring-actuated follower in said box operating to press the cigarettes laterally and maintain the foremost cigarette of the row opposite said opening, and formed with a catch member, an ejector operative to force said foremost cigarette through said opening, and a slidably mounted lock-bar having a catch member that, in the retracted position of said lock-bar, is automatically engaged by said follower catch member when said follower is moved to fully retracted position. 100

4. In a cigarette case, the combination of a box adapted to hold a row of cigarettes arranged side-by-side and having a delivery opening adjacent to one end of the 115 box and a hinged cover formed with a locking lug adapted, when the cover is closed, to extend through the front wall of the box, a spring-actuated follower-head formed with a catch, and a lock-bar slidably mounted on 120 the inner side of the front wall of the box and having a forked inner end adapted in its innermost position to engage said lug and lock the cover, and also having a tooth adapted in the outermost position of said 125 lock-bar to engage said catch and hold said follower-head in retracted position.

5. In a cigarette case, the combination of a box adapted to hold a row of cigarettes arranged side-by-side and having a delivery 130

opening adjacent to one end of the box, a follower comprising a follower-head adapted to laterally engage the rearmost cigarette of the row and formed with slotted side walls, a lazy tongs stem the arms of which are provided with cross-pins slidably engaging the slots of said side walls, and a tensile spring connecting the fol-

lower-head-engaging ends of said arms, and an ejector operative to force the foremost 1) cigarettes of the row through said opening.
